UNITED STATES PATENT OFFICE.

JOSEPH HIRSCHMANN, OF CHARLESTON, SOUTH CAROLINA, ASSIGNOR OF ONE-HALF TO
CHARLES R. ALLEN, OF CHARLESTON, SOUTH CAROLINA.

CHECK FOR PICKER-STICKS OF LOOMS.

1,323,055.

Specification of Letters Patent. Patented Nov. 25, 1919.

Application filed April 17, 1919. Serial No. 290,709.

To all whom it may concern:

Be it known that I, JOSEPH HIRSCHMANN, a citizen of the United States, and a resident of Charleston, in the county of Charleston 5 and State of South Carolina, have invented certain new and useful Improvements in Checks for the Picker-Sticks of Looms; and I do hereby declare the following to be a full, clear, and exact description of the invention, such as will enable others skilled in the art to which it appertains to make and use the same.

This invention relates to improvements in checks for the picker sticks of looms, the object being to provide a simple and inexpensive device for checking the movement of the picker stick due to the impact of an incoming shuttle upon the picker.

When the shuttle strikes the picker the 20 picker stick is thrown outward and such movement is assisted usually by a strap secured to the lower end of the picker stick and wound around a spring barrel. Such outward movement must be checked, but the 25 checking medium must be such that it will not impede the movement of the picker stick in the opposite direction. My invention meets these requirements and can be applied to any of the looms having a rocker resting 30 and rocking upon a shoe on the end of the rock shaft.

In the accompanying drawings; Figure 1 is a view in side elevation of a portion of a loom embodying my invention; Fig. 2 is a 35 view in section through the rocker, shoe and checking device, and Fig. 3 is a view in perspective of the yoke detached.

6 is a portion of a loom frame in which is mounted the rock shaft 7 carrying a rocker 40 shoe 8, and 9 is the picker stick having the rocker 10 secured to the lower end thereof in any well known manner. In many of the looms in use the lower end of the picker stick is secured to one end of a strap 11, the 45 opposite end of which is wound on a spring drum 12 journaled in bearings carried at the underside of the shoe 8, which operates to swing the picker stick outwardly, and the latter is moved inwardly, or in a direction to throw the shuttle across the lay, by 50 the lug-strap 13 connecting the stick with the pick-motion. The parts above referred to are used in looms employing a picker stick with a rocker foot, consequently may 55 be of any of the well known constructions.

My invention comprises an inverted U-shape metal frame or yoke 14, the free ends of which embrace the sides of the shoe 8 and straddle the inner free end of the rocker 10, and are secured to the former by a bolt 60 15 passing through elongated slots 16 in the side members of the yoke 14 and through a hole in the shoe, the bolt being secured by a nut 17, which when tightened on the bolt, operates to clamp the frame solidly to the 65 shoe. By loosening up the nut the yoke can be adjusted up or down as may be necessary and then secured by screwing the nut home.

Located within the yoke 14 and slotted at its ends to embrace the side members of the 70 latter, is the follower 18 to which the stem 19 is secured. This stem passes through a hole in the closed upper end of the yoke, and is embraced between the top of the yoke and the follower 18 by the spring 20 which operates to yieldingly hold the follower in the lowermost position. The upper end of the stem 19 is threaded for the attachment of the nut 21.

As above explained the yoke is adjustably 80 secured to the shoe and embraces the rocker foot, the latter resting below the follower 18 and in a position to engage the same at each rocking movement of the picker stick 9. The spring 20 is not sufficiently strong 85 to overcome the pull of the strap 11, by which the picker stick is thrown outwardly, but it is designed to absorb and check the movement at the end of its outward throw, without in the least interfering with the 90 effective movements of the picker stick. It is simple in construction, is of few parts; can be readily applied to any rocker and be so adjusted to bring the picker stick to a stop 95 without any lost motion or vibration.

It is evident that many slight changes might be resorted to in the relative arrangement of parts shown and described without departing from the spirit and scope of my invention. Hence I would have it understood that I do not wish to confine myself to the exact construction and arrangement of parts shown and described but,

Having fully described my invention what I claim as new and desire to secure by Letters-Patent, is:—

1. The combination of a shoe, a rocker thereon, a picker stick carried by the rocker, an inverted U-shaped yoke fixed with relation to the shoe and embracing the free end 110

of the rocker and a yielding follower carried by the yoke and forming a check for the rocker.

2. The combination of a shoe, a rocker thereon, a picker stick carried by the rocker, an inverted U-shaped yoke adjustably secured to the shoe and embracing the free end of the rocker, a movable follower carried by the yoke and above the free end of the rocker, and a spring backing for the follower.

3. The combination of a shoe, a rocker thereon, a picker stick carried by the rocker, an inverted U-shaped yoke adjustably secured to the shoe and straddling the free end of the rocker, a movable follower in the yoke, a threaded stem on the follower, the end of the stem passing through the closed end of

the yoke, a spring embracing the stem between the follower and closed end of the yoke and an adjusting nut on the free end of the stem.

4. The combination with a shoe, a rocker thereon and a picker stick carried by the rocker, of a yoke forming a check for the rocker said yoke being fixed with relation to the shoe and forming a yielding contact with the rocker.

In testimony whereof I have signed this specification in the presence of two subscribing witnesses.

JOSEPH HIRSCHMANN.
